UNITED STATES PATENT OFFICE

2,050,994

REFRIGERATIVE SYSTEM

John E. Dube, Chicago, Ill.

Application August 18, 1933, Serial No. 685,733

4 Claims. (Cl. 62—115)

The invention relates to refrigerative systems of the type wherein a liquid having a low boiling point, is vaporized and condensed; and, said invention, in its broadest aspect, involves two operating circuits, one of which contains the refrigerating liquid, and the other of which contains a motive liquid.

Said invention also involves details of construction which facilitate the operations of these two circuits, as well as the operation of the entire system.

The invention will best be understood if reference be had to the accompanying drawing in which—

15 Figure 1 shows one embodiment of the invention in elevation, parts of the apparatus being broken away to reveal details of construction, and

20 Figure 2 is a horizontal sectional view showing a modified detail of the apparatus.

The apparatus, as illustrated in said drawing, is provided with a separator tank 1 which contains two liquids 2, 3, the liquid 2 being the refrigerating liquid, and the liquid 3 being the motive liquid.

25 These two liquids should have different specific gravities in order that their stratification and separation in said separator tank, may adequately be effected, although, if found desirable, the stratification thereof may be aided by centrifugal force developed in any well-known manner. However, since any two liquids that may be employed will, before reaching the separation tank, be thoroughly blended, and since time is required for their separation, there will exist a zone intermediate the zones 2, 3, and indicated by the numeral 4, wherein the two liquids will always be mixed, although, in said zones 2, 3, they will be substantially, if not 30 entirely, separated.

40 It is, of course, preferable to select liquids which are, not only chemically stable as respects each other, but readily separable. The motive liquid 3 must be less volatile than the refrigerating liquid 2, and it may be water or oil, while said refrigerating liquid may be a known volatile hydrocarbon, or sulphur dioxide.

45 Leading from a point within and below the upper end of the tank 1 is a pipe 3 that is provided with any well-known pressure-regulating valve 6 for controlling the out-flow of the refrigerating liquid 2. This pipe communicates with the evaporator coil 7, and said coil leads to 50 an injector which comprises a casing 8 having

ends 9, 10 that respectively carry a contracted nozzle 11 and a Venturi-tube 12.

Said nozzle 11 is supplied with motive liquid flowing through an air-cooled coil 13 which leads from the lower end of the supply tank 1 to a rotary pump 14 that communicates with said nozzle, and the Venturi-tube 12 discharges into a tube 15 which carries the motive liquid mixed with condensed vapor into the tank 1.

5 Motive liquid cooled in coil 13 is forced by pump 14 through ejector 8 sucking out the refrigerant vapor from the coil 7 and compressing said refrigerant vapor. Said refrigerant vapor, though cooler than the high velocity liquid motive fluid before compression, is raised to a higher temperature than the motive fluid, that is, to a temperature which corresponds to the pressure after compression, so that heat is transferred from the high-temperature compressed refrigerant to the liquid motive fluid, causing the vaporized refrigerant to condense. Thereupon separation of the refrigerant from the motive fluid takes place in tank 1. The motive fluid then passes the coil 13 to repeat the cycle, and the refrigerant liquid passes through the regulating valve 6 to the refrigerating coil 7.

20 The rotary pump 14 is driven by an electrical motor 16 of usual construction, and the operation of said motor is controlled by a well-known thermostatic switch mechanism 17, 18, 19, 20, 25 30 21, the expansive element 17 of which is subjected to the heat of the evaporator coil 7.

35 In the modification shown in Figure 2, the pipe 15 enters the tank 1 at a tangent to its circumference, to thereby enable the inflowing blended liquids to impart a whirling motion to the contents of said tank, and aid the stratification and separation of said liquids by the aforesaid centrifugal action.

40 The several parts of the apparatus, hereinbefore described, excepting the pump and its stuffing box and the motor and its controlling mechanisms, are connected by fixed vapor-tight joints which prevent loss of the refrigerant and the motive liquid by leakage. Should any of the 45 motive liquid escape through said stuffing box, the loss will be compensated for by the expansion of the body of vapor in the zone 22 of the tank 1.

45 Thus far it has been assumed that the motive liquid is heavier than the refrigerating liquid, but if the reverse were the case, the refrigerating liquid would be disposed at the bottom of the tank 1, and an obvious rearrangement of the circuits would be required.

50 When the apparatus is to be operated, the 55

tank 1 is partially filled with the motive liquid 3, and upon this liquid is floated the liquid refrigerant 2. When said tank is thus charged, the pressure therein will be P , this being the pressure of the refrigerant at the temperature T .
5

The liquid refrigerant flowing through said pipe 5, passes into and actuates the pressure-regulating valve 6, and this valve is so adjusted as to maintain, in the evaporating coil 7, a low pressure p corresponding with the desired low temperature t . The liquid refrigerant, as it flows into the evaporating coil, expands into vapor, and draws the heat required for its vaporization from the medium surrounding said vaporizing coil.
10

15 The vaporous refrigerant, leaving the evaporator coil 7, enters the injector in which it is mixed with and condensed by the jet of motive liquid flowing from the nozzle 11. The pump 14 forces motive liquid, cooled in the coiled heat exchanger 13, into and through said nozzle, and since the temperature thereof has been reduced from T to T_1 , the quantity of heat removed therefrom will be equal to the quantity of heat taken from the medium surrounding the evaporator coil 7.
20

25 Said heat exchanger 13 may be air cooled, as shown, or it may be enclosed in a water tower. The kind of cooling apparatus employed will, of course, be determined by the required capacity thereof, by the desired differentials of temperature in the circuits of the system, and by the temperatures of the available cooling mediums.
30

35 The intake pressure of the pump 14, theoretically will be equal to the vapor pressure P in the tank 1, although, because of the frictional resistances in the coil 13, it will be less than P . Sufficient energy therefore must be applied to the pump 14, to enable it to raise the pressure of the motive liquid from P to P_1 , or to a pressure that is high enough to effectuate the work 40 performed by the jet issuing from the nozzle 11, and also to overcome the frictional resistances of the system.

45 The jet emanating from the nozzle 11, will entrain the vaporous refrigerant and carry it through the Venturi-tube wherein it is condensed. This condensation will take place even though the motive liquid has a higher temperature than the vaporous refrigerant, since said condensation is produced by compression. The compression 50 also reduces the volume of the refrigerant and produces a suction which enhances the efficiency of the jet.

55 It is of the greatest importance that the vapor pressure of the motive liquid, at temperature T , shall be less than the vapor pressure of the

refrigerant at temperature t , namely, the pressure p . If this were not so, the motive liquid, upon attaining a velocity high enough to reduce its static pressure below p , would vaporize and render the jet impotent.
5

On account of the condensation of the vaporous refrigerant in the jet of motive liquid, the temperature of that liquid in said jet, is raised from temperature T_1 to temperature T , so that a stream of mixed motive liquid and liquid refrigerant, at pressure P and temperature T , will enter the tank 1 through the pipe 15.
10

The system, as above stated, is controlled by the automatic switch mechanism herein described. This mechanism starts the motor 14 whenever the temperature of the medium being cooled rises above a pre-determined limit, and stops said motor when the temperature of that medium is sufficiently low.
15

The injector, instead of having a single nozzle, may be one of the multiple-nozzle type.
20

Having thus described my invention, what I claim is:

1. A refrigerative system, including at least two circuits respectively containing liquids having different boiling points and different specific gravities, said two circuits having a passage which is common to both of them and is provided with an injector in which the vapor of the refrigerating liquid is condensed by the motive liquid.
25

2. A refrigerating system including a refrigerant circuit and a motive fluid circuit, said refrigerant circuit comprising a separator, an expansion valve, an evaporator coil, and an ejector, in the order named, said motive fluid circuit comprising said separator, a cooling coil, a pump, and said ejector, in the order named, said cooling coil functioning to drop the temperature of the motive fluid before it reaches the ejector, so that as the ejector compresses the refrigerant 40 sucked out of the evaporator, it condenses it.
35

3. The apparatus as in claim 2, further characterized in that it includes an electric circuit and an electric motor therein for operating said pump and thermostatic means responsive to the temperature of the ambient about said evaporator coil for operating a switch in said electric circuit.
45

4. The apparatus as in claim 2 further characterized in that the said two circuits respectively have therein two liquids of different specific gravities and boiling points.
50
